UNITED STATES PATENT OFFICE

JAMES A. MOULD, OF MILWAUKEE, WISCONSIN

INTERNAL-COMBUSTION ENGINE

Original application filed October 21, 1927, Serial No. 227,656. Divided and this application filed September 18, 1928. Serial No. 306,770.

This invention relates to improvements in internal combustion engines.

It is the object of the invention to provide a novel and improved form of internal combustion engine of the type shown in the patent to Saunders, No. 1,463,595 and improved as to structure for the purpose of rendering it more efficient and less subject to breakage than has heretofore been possible. This is a 10 division of my application No. 227,656, filed October 21, 1927.

In view of the heat developed during normal operation, it is undesirable to have the fuel tank mounted directly upon the implement. Connections from the fuel tank to the 15 implement, however, must be of such a nature that no damage will result from the terrific vibration to which the parts are subject during use. It is one of the purposes of the 20 present invention to provide a novel and improved structure in which the fuel tank and carbureting device are unitarily mounted by a single set of bolts which connect the fuel tank unit directly to the manifold, thereby 25 dispensing with communicating tubing of any kind.

It is a further object of the invention to minimize difficulties heretofore experienced with carburetion in two cycle engines. Such 30 engines are frequently very hard to start due to "flooding" by excess of fuel at the carburetor. The present invention contemplates the elimination of difficulties of this character not through any change in the carburetor, but through a modification of manifold 35 design whereby the charge compressed below the piston is impelled past the mixing valve or carburetor on its way to the combustion chamber, whereby to sweep the manifold free 40 from accumulations of liquid fuel therein.

Another object of the present invention has reference to the assembly of the several parts in a device of this character whereby 45 construction and repair of the tool is simplified and the cost of manufacture minimized. Other objects include the provision of means for minimizing heat transference through the solid piston required for the purposes of this tool the provision of a novel and 50 convenient set of handles for controlling the op-

eration of the tool and enclosing lead wires from a suitable battery, the provision of a novel and improved timer, and means other than the timer for guiding the piston.

In the drawing:

Figure 1 is a vertical axial section through a device embodying this invention in the plane indicated at 1-1 in Figure 2.

Figure 2 is a plan view of the tool.

Figure 3 is a bottom view of the tool.

Figure 4 is a section taken in the plane indicated by line 4-4 in Figure 1.

Figure 5 is a section taken in the plane indicated by line 5-5 in Figure 1.

Figure 6 is a view taken in section in the plane indicated at 6-6 in Figure 1.

Figure 7 is a fragmental detail of the breather tube taken in section in the plane indicated by line 7-7 in Figure 1.

Figure 8 is a fragmentary view partly in section, of the tool showing the needle valve arrangement.

Like parts are identified by the same reference characters throughout the several views.

The body of the tool comprises three principal parts including the cylinder casing 10, bottom cap member 11 and top cap member 12. The bottom cap member has ears 13, while a retaining ring 14 applied to the top cap member 12 has corresponding portions connected to said ears by means of the tension bolts 15. These two tension bolts hold the entire assembly together and upon unscrewing their respective nuts, all the interior parts of the mechanism may be exposed immediately for removal or replacement.

The cylinder casing 10 is provided internally with a cylinder 16 in which the piston 17 is reciprocable. The piston carries integrally a hammer 18 adapted in or near the extreme piston position to strike the anvil 19 which is connected to a plunger 20 guided within the lower end of the cylinder casing. Plunger 20 resets directly upon the end of the drill, chisel, or other tool 21 which is loosely received in the bore 22 of the bottom cap plate 11 and held in place in the usual way by the pivoted catch or detent 23. The cap member is provided with a resilient

cushion 24 positioned to take the hammer blow upon anvil 19 when the tool is not being held against the work. A packing ring is preferably used at 25 to prevent the possible escape of gas past plunger 20.

The downward movement of piston 17 compresses a supporting spring which has a portion 30 of normal strength and a stronger portion 31 which has a strength exceeding that required for the support of the piston. It is possible that both of these spring portions may comprise an integral part of a single spring, one end of which is relatively heavy and the other of which is relatively less heavy. In the interests of simplicity of manufacture, however, it is preferred to use two separate springs of ordinary helical form and preferably wound in opposite directions so as to obviate the necessity which would otherwise exist for an intermediate floating spring seat.

The interior portion of cylinder casing 10 in which the springs are housed serves as a compression chamber for compressing carbureted gases on their way to the combustion chamber. The fuel support means will now be described.

Casing 10 has a boss 33 having ports 34 and 34' separated by an intervening web 35. 30 The fuel tank and carbureting device comprise a unitary structure shown at 36 in which a fuel reservoir 37 is supplied with fuel through filler cap 38. To the bottom of unit 36 is applied a valve fitting 39 which carries an air valve 40 in passage 41 and a needle valve 42 in a duct leading at 43 from a screened outlet in the bottom of the reservoir 37 and opening at 44 to the seat of the air valve so that the passage of air lifting valve 40 from its seat will create an aspirating effect tending to draw a predetermined ratio of fuel through the discharge duct 44 in the usual way. The air passage 41 is extended upwardly beneath an overhanging visor 45 as shown in Figure 3 to eliminate dust so far as is possible.

An annular shoulder 48 surrounds the end of manifold section 47 and is adapted to engage upon the outer periphery of boss 33. 50 Two bolts at 49 mount the fuel and carburetion unit rigidly upon the engine and comprise the only mounting means. It is particularly to be noted that the connection is made at a point well below the combustion chamber and that the fuel tank is spaced from the heated portions of the engine. As a matter of fact, it is spaced from the engine at all points except its point of connection upon boss 33 which is cooled by the gases admitted to the manifold.

Formed integrally within fuel unit 36, is a manifold divided centrally by a web 47 arranged to register with web 35 and terminating at 47' immediately adjacent the valve 40. 60 The manifold passage at one side of this web

communicates with port 34, while the manifold passage at the other side of the web communicates with port 34'. Port 34 leads to the compression chamber below the piston as is clearly shown in Figure 1, while port 34' leads to a manifold 51 through which the compressed carbureted mixture is admitted through ports 52 to the combustion chamber. It will be obvious therefore that the only communication between the compression chamber below the piston and the combustion chamber above the piston is through port 34 and the manifold at one side of partition 47 to a point adjacent the mixing valve 40 and then upwardly along the other side or partition 47 through port 34' and manifold portions 50 and 51 to the inlet ports 52.

The inlet ports are intermittently uncovered by the cut-away portion 53 of piston 17. During the compression stroke of the piston the energy stored in compression spring 30, air entering through pipe 41 will open valve 40 and enter the manifold passage shown in Figure 1 leading through port 34 to the compression chamber below the piston, such air will be carbureted in its passage between valve 40 and the seat thereof. During the expansion stroke, products of combustion will escape through exhaust port 53' leaving a partial vacuum in combustion chamber 16 into which the compressed gases in the compression chamber will rush through the set of communicating passages which will lead such gases back across the surface of the mixing valve, whereby to pick up and sweep from the passage any possible accumulation of liquid fuel therein. This arrangement whereby the entire manifold system clear to the face of the mixing valve is swept by the compressed charge entering the cylinder at the time port 52 is uncovered, is regarded as of considerable importance and in practice has been found to eliminate difficulties heretofore experienced in the way of "flooding" in two cycle engines.

In this embodiment of the invention battery ignition is contemplated from some outside source of current. The compressed gases in combustion chamber 27 are ignited by a spark produced between the electrodes 54 of spark plug 55 when contact is established to ground through the timer mechanism 56.

The timer includes a contact plunger 57 which rides on the face of the piston to enter groove 58 therein. Plunger 57 is grounded at all times to the body of the machine. Insulated from such body by a dielectric liner 59, is a stationary contact 60 connected by spring 61 with binding post 62, the arrangement being such that when plunger 57 is forced by its compression spring 63 into groove 58 near the lower end of the piston, contact will be established between the plunger and the stationary contact 60 to complete

a circuit through ground to the grounded electrode of spark plug 55.

It will be observed that in its uppermost position, the piston has moved the spring 5 groove 58 out of registry with plunger 57. The arrangement is such as to time the ignition slightly in advance of the end of the piston stroke for maximum efficiency. At the same time, the timer contact is open in the 10 uppermost position of the piston, thereby avoiding possible waste of current when the apparatus is not in use.

Pin 65 projecting into the cylinder casing from its side enters a longitudinal groove 15 66 in piston 17 and thereby serves to guide the piston and to maintain the channel or depression 58 in registry with the end of plunger 57. This arrangement avoids wear on the timer and plunger such as might cause it to bind or stick if it performed the guiding function in addition to its function of reciprocation. In this arrangement, the timing plunger rides normally directly upon the exterior surface of the piston.

25 Due to the use of a solid piston, there is a tendency for the interior of the piston to become excessively heated. This is avoided in part by the use of a symmetrical series of bores 68 and 69 which extend radially immediately beneath the face of the piston and, in effect, provide a symmetrically and uniformly honeycombed piston head. This feature is more fully disclosed in my application Serial No. 227,656 filed October 21, 1927 and, 30 since no claims are directed to this feature in this application, it is deemed unnecessary to burden the present case with further details. The air contained in these bores insulates the body of the piston from the heat 40 of the combustion chamber. The symmetry of the bores is desirable in order to avoid unequal heating and corresponding unequal expansion of the piston.

Overheating is also avoided by the use of 45 an extended cooling system. It will be obvious that the cooling fins applied directly to the cylinder wall in Saunders Patent No. 1,463,595 have a definitely limited area. I have found it desirable in my improved engine to increase this area and this is accomplished by forming fins or breather rings 50 68 upon the outer periphery of a jacket 70 instead of upon the cylinder itself. Not only is the jacket of considerably larger diameter 55 than the cylinder, thereby increasing the area of the fins without increasing their length; but, moreover, it will be obvious that the jacket may be extended as at 71 far above combustion chamber 27, thereby making room 60 for an additional number of fins 68'. The jacket space 72 encircles the wall of cylinder 16 and extends upwardly within the jacket extension as at 73. The jacket space is adapted to receive a liquid such as oil or the like 65 which, by its convection currents, will carry

heat from the cylinder to the entire periphery of the jacket. The heat is then dissipated through fins 68, both by radiation and by air currents set in motion by the annular plates 75 described in Saunders Patent No. 1,463- 70 595, the inertia of such plates causing them to move between consecutive cooling flanges during the vibratory operation of the piston, whereby to force air in and about such flanges.

75 The engine is started in a well known manner by manually depressing and suddenly releasing the spring supported plunger 77.

While the engine is in operation, it is conveniently manipulated and guided by the 80 tubular handles 80 which are formed integrally with the clamping ring 14 and project laterally in a radial direction therefrom. One of these handles serves as a guide and conduit for the ignition wires 81 which lead 85 to the conveniently located cut-off switch 82 and thence to the spark plug 55 and timer 56 as previously described.

While it will be obvious from the foregoing description that the particular embodiment 90 of this invention which is herein disclosed fully cites the specified objects, nevertheless, I do not regard the invention as limited to this particular embodiment and wish to point out that various modifications may be made 95 within the spirit and intent of the above description and appended claims.

I claim:

1. In a device of the character described, the combination with an engine provided 100 with a manifold, of a fuel supply tank communicating with the manifold and connected with said engine for support thereby solely at said manifold.

2. In a device of the character described, the combination with an engine provided with an intake manifold port, of a fuel supply tank provided with a manifold section adapted to register with the manifold port of said engine, means wholly adequate for carrying said tank and connecting said tank to said engine adjacent said port, and a carbureting means associated with said tank and mounted therewith, said tank being spaced from said engine except adjacent said port. 110

3. The combination with an engine provided with a manifold having an inlet port in a projecting boss, of a fuel supply tank, a carbureting unit provided with a manifold section registering with said port, valve 120 means controlling the admission of air and fuel to said last mentioned manifold section, and means connecting said unit with said boss, said unit being spaced from said engine except at said boss. 115

4. The combination with an engine provided with a manifold having an inlet port in a projecting boss, of a fuel supply tank, a carbureting unit provided with a manifold section registering with said port, valve means 125

controlling the admission of air and fuel to said last mentioned manifold section, means connecting said unit and said boss, said unit being spaced from said engine except at said boss, and being provided with a flange interengaging with said boss.

5. The combination with an engine provided with an intake manifold and a port opening through a lateral boss in communication 10 with said manifold, of a fuel tank unit secured to said engine solely at said boss and in spaced relation thereto except at the point of connection therewith, said unit comprising a storage tank for fuel, a manifold section 15 communicating with said port and opening to the atmosphere, a check valve in said section, and a fuel duct adapted to supply fuel from said tank to air traversing said manifold section.
- 20 6. In a device of the character described, the combination with an engine provided with a laterally opening port, of a fuel tank unit secured to said engine only at said port and supported therefrom in spaced relation 25 at other points, a supply tank in said unit, a manifold section communicating with said port and extending beneath said tank, a check valve in said section controlling communication of the atmosphere with said port, and 30 means for supplying fuel to air traversing said section.

7. In a device of the character described, the combination with a cylinder providing combustion and compression chamber spaces 35 and a piston reciprocable therein, of a boss on said cylinder provided with ports communicating respectively with said spaces, a fuel supply unit secured to said boss and provided with passages communicating with the respective ports therein and united adjacent an additional port in said unit comprising the sole means for admitting gases to said spaces, and a valve controlling said last mentioned port and exposed to gases passing from the compression chamber space to the combustion chamber space through said passages.

8. In a device of the character described, the combination with a piston, of a cylinder provided with a compression chamber, a combustion chamber, a boss upon its side, and passages leading from said chambers and opening at said boss, a fuel supply unit mounted upon said boss and provided with an inlet port and passages leading therefrom to register with the passages opening at said boss, and a mixing valve controlling said port and comprising the sole means for admitting gases to the compression chamber, whereby gases so admitted must pass adjacent said valve in traversing said passages from the compression chamber to the combustion chamber.

9. In an internal combustion engine, the combination with a cylinder having a combustion chamber and a compression chamber

and a port leading from each of the chambers to the exterior thereof, of a fuel tank unit connected with said cylinder and supported solely therefrom including a storage tank an air inlet and a pair of passages each connected with one of said ports, and a carbureting chamber connecting said tank, said inlet and said passages.

10. In an internal combustion engine, the combination with a cylinder having a combustion chamber and compression chamber and a wall provided with laterally adjacent ports communicating with the respective chambers, of a carburetion unit affording the sole means of communication between said ports and connected with said cylinder around said ports, said unit comprising a pair of passages terminating in registry with the respective ports, a carburetion chamber affording communication between said passages and provided with an air admission port immediately adjacent the point of communication aforesaid, a valve controlling flow through said air admission port, and means for supplying a hydrocarbon to said carburetion chamber.

11. In an internal combustion engine, the combination with a cylinder having a combustion chamber and compression chamber and a wall provided with laterally adjacent ports communicating with the respective chambers, of a carburetion unit affording the sole means of communication between said ports and connected with said cylinder around said ports, said unit comprising a pair of passages terminating in registry with the respective ports, a carburetion chamber affording communication between said passages and provided with an air admission port immediately adjacent the point of communication aforesaid, a valve controlling flow through said air admission port, and means for supplying a hydrocarbon to said carburetion chamber, said unit including also a storage tank for hydrocarbon fuel supported wholly from said cylinder through the connection of said unit with the cylinder aforesaid.
